MAGNETIC GUIDE FOR TOOLS

Charles S. Finnell, Oklahoma City, Okla.

Application March 24, 1941, Serial No. 385,017

3 Claims. (Cl. 143—89)

This invention relates to guides for reciprocating tools such as saws, files and the like.

The invention contemplates the use of a magnet as a guiding means for a reciprocating tool. Various modifications of this generic idea of using a magnet as a guide for tools are illustrated in the accompanying drawing, in which

Figure 1 is a rear view of the guiding magnet employed to guide an ordinary carpenter's hand saw;

Fig. 2 is a plan view of the structure such as is illustrated in Fig. 1;

Fig. 3 is a detailed plan view illustrating that the magnet may be an electromagnet;

Fig. 4 is a side elevation of an ordinary hack saw carrying a guide plate adapted to cooperate with a magnet;

Fig. 5 is a plan view of the structure of Fig. 4, and;

Fig. 6 is a plan view illustrating a guide plate and support thereon, in which a file or like tool is mounted.

Like numerals designate corresponding parts in all of the figures of the drawing.

All forms of the invention contemplate the use of a magnet of any suitable size and shape adapted to engage with the flat, true surface of a tool itself, such as the blade of a hand saw, S, or a flat, true guide plate from which the tool is supported. Consequently, in all of the figures the magnet has been designated by the same reference character, 5, except that in Fig. 3 the magnet has been designated 5^a because in that figure the magnet is indicated as being an electromagnet.

The magnets may be held against movement in any suitable way. In Fig. 1, 6 indicates a work table, 7 a piece of wood being sawed, and 8 a suitable support for supporting the magnet from the table. The support 8 is preferably of non-magnetic material. The magnet may be rigidly affixed to the support 8, or it may be made separate from the support, as shown, and be mounted to turn upon a stud 9 that is carried by the support. A binding nut 10, will, in that event, serve to bind the magnet in fixed relation to the support 8.

Further, the magnet may be provided with graduations 11, adapted to cooperate with the pointer 12, said pointer being carried by the support 8. The magnet is supported from the stud 9 by means of its hub-like portion 14 which embraces the stud 9 and underlies the binding nut 10. By providing the pointer and graduations

as described, and by mounting the magnet to turn upon the stud 9, this magnet guide may be caused to serve all of the functions of a mitre box. Such an arrangement will be not only much less expensive than the known forms of mitre boxes but will be more convenient to use.

In many of the known forms of mitre boxes it is necessary to thread the saw endwise through the guiding element. This is not the case with 10 my invention, wherein the saw may be brought sideways and toward the magnet and be held by magnetism alone.

In Figs. 4 and 5 I have illustrated a conventional hack saw 15 having a guide plate 16 secured to the rear side of its frame. This plate may be secured in position by screws 17, or it may be welded to the plate 15. In any event, its rear face 18 must be polished, straight and true so that it will slide easily with respect to its guide magnet 5.

In the form illustrated in Fig. 6, a like straight and true guide plate 19 adapted to be magnetically attracted by magnet 5 carries a file 20 and functions as a holder for said file. Any suitable reciprocating tool may be mounted in a tool holder having a flat guide surface adapted to engage a magnet as described.

From the foregoing description it will be apparent that the invention resides not only in the particular embodiments shown, but more generally in the thought of utilizing a magnet (with a simple, permanent magnet or an electromagnet) as a guide means for a tool, in such fashion that engagement of tool and magnet may be effected by the simple lateral approach of the tool, or equivalent tool holder, toward the magnet.

While I have made frequent reference to the reciprocating type of tools, I wish it to be understood that the invention includes the guiding of any tool suitable for use in connection with a magnetic guide whether such tool be reciprocating, rotary, oscillatory or other wise.

Consequently, it is to be understood that the invention includes within its purview not only the particular arrangements illustrated, but such modifications thereof as fairly come within either the terms or the spirit of the appended claims.

Having described my invention, what I claim 50 is:

1. The combination with a tool of a nature to cut under its longitudinal reciprocation and provided with an elongated flat, true face extending in the direction of the length of the tool and in parallelism with the stroke of the tool,

and a magnet disposed to engage said face and hold the tool against lateral movement while permitting its longitudinal reciprocation.

2. The combination with a support for work to be cut, of a reciprocating cutting tool comprising an elongated flat metallic surface, and a magnet mounted in such relation to the support as to attract and hold said metallic surface of the tool at a determined angle with respect to the support and work during the reciprocation of the tool in the act of cutting. 10

3. The combination with a support of a nature to receive work to be hand sawed, of a magnet supported for adjustment to a plurality of angles and in such relation as to magnetically engage the flat side of a carpenter's hand saw and guide the same at the proper angle to cut work placed on said support, said magnet presenting a flat face over which the hand saw may slide. 5

CHARLES S. FINNELL.
